UNITED STATES PATENT OFFICE.

BROR JOHAN JOHANSSON, OF MILWAUKEE, WISCONSIN, ASSIGNOR OF ONE-FOURTH
TO ANDREW M. OLESTON, OF MILWAUKEE, WISCONSIN.

HUMIDIFIER.

Application filed May 12, 1924. Serial No. 712,631.

This invention relates in general to improvements in the art of conditioning gases, and relates more specifically to an improved humidifier which is capable of automatically maintaining a proper percentage of moisture in the air confined within buildings or the like.

An object of the invention is to provide a humidifier which is simple in construction and efficient in operation.

Some of the more specific objects and advantages attainable with the present improvement are as follows:—

To provide an extremely compact and automatically functioning humidifying device which is especially adapted for use in residences, schools, hospitals, offices and the like.

To provide a humidifier which is highly efficient in operation and which may be manufactured and sold at minimum cost.

To provide apparatus for imparting moisture to the atmosphere, which may be readily cleaned and maintained in operating condition.

To provide a neat and ornamental humidifier which is capable of convenient attachment to standard radiators and the like, and which may be rapidly removed when desired.

To provide a device for air humidification, which has extremely large evaporating surfaces and which is formed to permit free access and flow of air along such surfaces.

To provide a sectional humidifier which may be increased or diminished in size and capacity, at will.

To provide a humidifying device which may be manufactured from earthen material in various shapes and sizes in order to meet various conditions of use.

These and other objects and advantages resulting from the present invention, will be apparent in the course of the following description.

A clear conception of a number of embodiments of the present improvement and of the operation of devices constructed in accordance therewith, may be had by referring to the drawing accompanying and forming a part of this specification in which like reference characters designate the same or similar parts in the various views.

Fig. 1 is a front elevation of a preferred form of the improved humidifier.

Fig. 2 is a transverse vertical section through the humidifier of Fig. 1.

Fig. 3 is a top view of the humidifier of Figs. 1 and 2.

Fig. 4 is a transverse vertical section through another form of improved humidifier having the same general external shape as that disclosed in Figs. 1, 2 and 3.

Fig. 5 is a top view of another form of improved humidifier having a flower box associated therewith.

Fig. 6 is an end elevation of the humidifier shown in Fig. 5.

Fig. 7 is a top view of still another form of improved humidifier with the cover thereof removed.

Fig. 8 is a central vertical section through the humidifier of Fig. 7.

Fig. 9 is a top view of a relatively simple form of improved humidifier.

Fig. 10 is a central vertical section through the humidifier of Fig. 9.

Fig. 11 is a top view of still another form of improved humidifier.

Fig. 12 is a central vertical longitudinal section through the humidifier of Fig. 11.

Referring to the form of humidifier disclosed in Figs. 1, 2 and 3, the device comprises in general a receptacle 2 formed of permeable substance, preferably porous

earthen material such as baked clay, the receptacle 2 being divided into two relatively deep and long liquid compartments 3 which are separated by a vertical air duct 10.

A single trough 4 formed integral with one end of the receptacle 2, serves to simultaneously supply liquid such as water to both of the otherwise segregated compartments 3.

While the central air duct 10 is entirely free from obstruction, each of the water compartments 3 may be provided with a plurality of reinforcing ribs 6, and the bottom of the receptacle 2 may also be provided with transverse strengthening ribs 9. The front of the receptacle 2 directly below the forward compartment 3 is preferably provided

with a single relatively long horizontal air inlet opening 7 for conducting air to the central duct 10, and the back of the receptacle 2 may also be provided with a series of circular openings 8 for performing a similar function.

The rear wall of the receptacle 2 is provided with one or more integral lugs 5 with which the receptacle suspension hooks 11 cooperate. The hooks 11 are so

100
105
110

110

formed as to permit effective suspension of the receptacle 2 from various standard hot water or steam radiators. The receptacle 2 may obviously be made of any desired length 5 and capacity depending upon the specific characteristics of the room which is to be humidified.

Referring to the form of humidifier disclosed in Fig. 4, the device comprises in general 10 a receptacle 12 formed of permeable material such as porous earthen substance, and is divided into two relatively long, deep pockets or liquid compartments 13 which are separated by an unobstructed vertical air duct 14. The general external shape of the receptacle 12 is the same as that of the previously described receptacle 2. The rear wall of the receptacle 12 is provided with one or more integral lugs 15 with which suspension hooks 16 are adapted to cooperate. 15 These hooks 16 as previously stated in connection with the description of the hooks 11, are formed for coaction with standard radiators and with heating pipes, and the receptacle 12 may be modified in shape and 20 size to meet various conditions of operation. 25

Referring to the form of humidifier disclosed in Figs. 5 and 6, the device comprises several independent similar receptacles 17 30 formed of permeable earthen material or the like, and each having therein a relatively deep liquid confining compartment 18. One end of each receptacle 17 is provided with a vertical dovetail tongue 20 which is adapted 35 to coact with a dovetail groove 21 in the opposite end of an adjoining receptacle 17 to lock these receptacles together. The rear wall of each receptacle 17 may also be provided with a suspension lug 22 as shown, and 40 the medial rear portions of the receptacles 17 are preferably provided with lateral recesses 19. The recesses 19 are preferably of such shape that they will fit over the edges 45 of successive sections of standard sectional radiators and the receptacles 17 may be held in place against such a radiator by means of wire hooks coacting with the lugs 22. With 50 this form of receptacles 17, the humidifier may be readily enlarged or diminished by adding or removing sections. As shown, the receptacles 17 are provided with locking recesses 24 for the purpose of sustaining a flower box 23 or other ornamentation, in front of the humidifier.

55 Referring to the form of humidifier disclosed in Figs. 7 and 8, the device comprises an outer cylindrical cup shaped receptacle 25 and an inner cylindrical cup shaped receptacle 26, the former of which may be formed of any suitable substance and the latter of which is preferably formed of permeable earthen material. The inner receptacle 26 forms a compartment 28 for confining liquid, and may be provided with a 60 removable perforated cap 31. The outer re-

ceptacle 25 has an internal bore which is somewhat greater than the external diameter of the inner receptacle 26, the latter being held centrally within the former by means of lugs 27 and the two receptacles being separated by the annular air duct 30. An opening 32 in the bottom of the outer receptacle 25 permits entry of air upwardly 70 to the air duct 30. The wall of the outer receptacle 25 may be provided with an integral suspension lug 29 for supporting the humidifier from a radiator or the like. 75

Referring to the form of humidifier disclosed in Figs. 9 and 10, the device comprises a single cup shaped receptacle 33 80 formed of permeable earthen material or the like and having a relatively deep liquid confining compartment 34 therein. The rear of the receptacle 33 is provided with an integral lug 35 with which a suspension hook 36 85 is adapted to cooperate. The humidifier disclosed in these figures represents perhaps the simplest commercial embodiment of the invention aside from a plain porous jar. 90

Referring to the form of humidifier disclosed in Figs. 11 and 12, the device comprises a single receptacle 37 forming an enclosed liquid confining compartment 38 and having an upright marginal rim providing an open trough 41 surrounding the compartment 38. The receptacle 37 is preferably formed of porous earthen material and in view of the fact that this device is adapted to be set directly upon a table or the like, 95 the bottom should be waterproofed as by glazing. The compartment 38 is accessible from the top by virtue of a removable plug 39 and may have a constricted liquid discharge opening 40 near the bottom for the purpose of permitting direct flow of a small 100 amount of liquid directly to the trough 41 from the compartment 38. 105

The operation of all of the humidifiers illustrated is practically the same. During 110 normal operation of the devices, the liquid confining compartments are supplied with a suitable quantity of water which slowly percolates through the porous compartment walls and is gradually and continuously 115 evaporated by the dry air passing along the wetted compartment surfaces. If the evaporation is rapid, the percolation automatically becomes more rapid, and vice versa. The only requirement for continued automatic operation of the devices, is that the 120 compartments be properly supplied with water, which may also be done automatically if a source of continuous supply is available.

In the form shown in Figs. 1, 2 and 3, the air besides passing upwardly along the outer receptacle walls, is admitted through the openings 7, 8 and passes upwardly 125 through the air duct 10 and along the inner walls, thus producing a compact humidifier of large capacity. In the form shown in Fig. 130

4, the air passes upwardly along the outer wetted walls of the receptacle 12 and also flows upwardly through the central air duct 14, thus likewise producing a compact humidifier of large capacity. In the form shown in Figs. 5 and 6 and in the form shown in Figs. 9 and 10, the air merely passes along outer wetted surfaces. In the form shown in Figs. 7 and 8, the air is humidified while passing upwardly through the annular air duct 30, while the humidifier of Figs. 11 and 12 presents both a wetted wall and the exposed water in the trough 41.

By attaching the humidifier directly to a radiator as is possible with all embodiments illustrated, except that of Figs. 11 and 12, the efficiency of the devices is greatly augmented. The heated air has greater affinity for moisture and therefore more rapidly evaporates the moisture from the exposed surfaces. The various receptacles may be conveniently manufactured from clay which may be machine molded and subsequently baked. The filling trough 4 serves to simultaneously supply liquid to both of the compartments 3 in the humidifier of Figs. 1, 2 and 3 and the sectional construction of the device of Figs. 5 and 6 permits ready variation of the capacity thereof.

30 From the foregoing description it will be obvious that humidifiers constructed in ac-

cordance with the present invention besides being extremely simple in construction and efficient in operation, may be manufactured and sold at relatively low cost. These devices may be readily removed from their normal supports and are conveniently accessible for cleaning and filling. 85

It should be understood that it is not desired to limit the invention to the exact details of construction herein shown and described for various other modifications within the scope of the claims may occur to persons skilled in the art. 40

It is claimed and desired to secure by Letters Patent: 45

1. A humidifier comprising two series of laterally spaced receptacles formed of porous earthen material and having an air conducting conduit disposed between said series 50 and extending vertically throughout the length of said receptacles.

2. A humidifier comprising two series of integrally united laterally spaced communicating receptacles formed of porous earthen 55 material and having a plurality of air conducting conduits separating said series and extending vertically throughout the length of said receptacles.

In testimony whereof, the signature of the 60 inventor is affixed hereto.

BROR JOHAN JOHANSSON.
